UNITED STATES PATENT OFFICE

AUBREY M. KENNEDY, OF LOS ANGELES, CALIFORNIA

SOUND-REPRODUCING MECHANISM FOR RADIOS

Application filed August 3, 1929. Serial No. 383,270.

The object of the present invention is to provide means for use in radio broadcasting and receiving for reproducing sound either in the sending or the receiving of the sound waves. Specifically the invention relates to apparatus comprising magnetically actuated tuned diaphragms incorporated in either radio broadcasting devices or in loud speakers for reproduction of broadcast sounds, the diaphragms being so related to the actuating magnets that they may be selectively actuated in accordance with the character of the sound waves.

The invention will be described with reference to the accompanying drawings, in which—

Figure 1 is a plan view, of an embodiment of the invention, and

Figure 2 is a sectional elevation of the same; Figure 3 is a modified form of the apparatus;

Figure 4 is a schematic view in elevation of an embodiment of the invention in conjunction with a microphone for broadcasting;

Figure 5 is a view in sectional elevation of a further modification, and

Figure 6 is a plan view of the same.

In the present practice of radio broadcasting and receiving, a diaphragm is employed in both the microphone and loud speaker which is selected for its average efficiency in the translation of the magnetic electric impulse into vibrations or sound waves. The same diaphragm is used for a symphony orchestra as for a violin solo, and that used for a choir is the same as used for a single voice. It is impossible to construct one diaphragm which will be suited to all musical or other sound vibrations. If a diaphragm is so constructed as to be particularly adapted for the sending or reproduction of vibrations of high pitch, that diaphragm will not ordinarily be adapted for the best reproduction of low pitch vibrations, and there are other conditions which restrict a diaphragm of a given construction.

Referring to Figures 1 and 2 of the drawings, it will be seen that 1 is a casing in which are mounted seven diaphragms indicated by the letters A to G inclusive. Above each dia-

phragm the casing is formed with an outlet indicated at 2, and the outlet may communicate with a horn or other amplifying member. Within the casing and adapted for registry with each one of the seven diaphragms is the magnetic reproducing assembly 3 which may be of usual construction. The reproducing assembly, in the said embodiment, is fixed, whereas casing 1 is movable, longitudinally, so that the diaphragms may selectively be brought into register with the reproducing assembly. Each diaphragm may be tuned to a note in the standard musical scale. Assuming the device to be constructed as a loud speaker and a violin solo is to be reproduced, the diaphragm tuned to that particular vibration is used, for example diaphragm F. The casing is moved to a point where the reproducing assembly will actuate that diaphragm. Assuming that the device is employed as a broadcasting assembly, the action will be the same. For example, announcement may be made by the broadcaster that a violin solo is to be broadcast and the direction given to use diaphragm F, which will be the diaphragm used by the broadcaster, and those listening in may accommodate their loud speakers to diaphragm F.

Tuning of the diaphragms may be accomplished by various methods, as for example, difference in thicknesses of the diaphragms, differences in materials used, differences in sizes, etc.

In the structure of Figure 3 the diaphragms are carried by a slideable frame member 4 and the reproducing assembly is fixed within a casing 5. The casing is provided with aligned apertures for the passage of the slideable frame 4 so that the diaphragms may be selectively placed in register with the reproducing assembly.

In the construction shown in Figure 4, the diaphragms are carried by a rotatable frame member 6 movable about an axis 7. At 8 I have shown, diagrammatically, a microphone, the microphone being so related to frame member 6 that the diaphragms may be successively brought into operative register with the microphone for actuation by the magnetic elements thereof. Any suitable

means may be employed for maintaining the diaphragms in juxtaposition to the microphone magnetic elements, as will be understood by those skilled in the art.

In Figures 5 and 6 I have shown a casing 9, a magnetic assembly 10, and means for removably supporting any one of a plurality of diaphragms, one of the diaphragms being shown at 11. In the front wall of the casing 5 an aperture 12 is provided through which the diaphragms may selectively be passed. Arranged in annular formation within casing 9 are a plurality of lower leaf springs 13 supported by annular member 14 of the casing 10 and supported by the top wall 9^x of the casing are a plurality of leaf springs 13^x, arranged in annular formation. Each diaphragm may be provided with a handle 20 by means of which the diaphragm may be 20 passed through aperture 12 and between the two sets of springs so as to be held firmly in position. Springs 13 may be stronger than springs 13^x and above springs 13^x may be placed a rigid metallic ring 21 in register 25 with set screws 22, by means of which the ring may be moved downwardly so as to carry the diaphragm toward the pole pieces 23 of the magnetic assembly 10. By reversely rotating the thumb-screws the strongest 30 springs 13 raise the diaphragm. An equivalent adjustment may be provided for the member 4 illustrated in Figure 3.

Having described my invention, what I claim and desire to secure by Letters Patent 35 is as follows:—

1. In radio reproducing mechanism, in combination with a magnetic assembly of a support, diaphragm holding means in said support and a diaphragm provided with a carrier, the diaphragm being so related to the holding means that it may be moved into the support and gripped by the holding means 40 for coaction with the magnetic assembly, and removed therefrom by withdrawal in the 45 plane of its face.

2. A device constructed in accordance with claim 1, in combination with means for actuating the diaphragm toward and from the magnetic assembly in a direction transverse 50 to the plane of the diaphragm face.

In testimony whereof, I have signed my name to this specification.

AUBREY M. KENNEDY.
